[57] CLAIM

The ornamental design for an exercise bar for physical exerciser, as shown and described.

DESCRIPTION

FIG. 1 is a front elevational view of an exercise bar for physical exerciser showing my new design, the side opposite being substantially a mirror image;

FIG. 2 is a bottom plan view thereof;

FIG. 3 is a top plan view thereof; and,

FIG. 4 is a side elevational view thereof.
